UNITED STATES PATENT OFFICE.

LLEWELLYN REECE, OF NEW YORK, N. Y.

NOTE OR CHECK AND PROCESS OF PRINTING THE SAME.

1,261,292.

Specification of Letters Patent.

Patented Apr. 2, 1918.

Application filed March 16, 1909. Serial No. 483,747.

To all whom it may concern:

Be it known that I, LLEWELLYN REECE, a subject of the King of Great Britain, and a resident of the city of New York, borough 5 of Manhattan, in the county and State of New York, have invented a new and Improved Note or Check and Process of Printing the Same, of which the following is a full, clear, and exact description.

10 My invention relates to negotiable instruments and other commercial paper printed upon what is commercially known as safety paper, and the process or method of producing this paper, and these notes, checks 15 or other commercial papers.

The main object of my invention is to provide safety paper of the character described wherein the ground color while being highly sensitive to chemicals which 20 might be used thereon, will be insensible to moisture so as to avoid the smutting of the paper through the ordinary handling thereof. A further object is to provide a paper of the character above referred to, wherein 25 the fibers of the paper will be so permeated with the coloring matter as to cause any chemical, which might be applied thereto for the purpose of removing the color, to act upon the fibers thereof in a manner so 30 as to deface it and prevent its restoration to its former condition, thus making forgery through erasure and restoration extremely difficult, if not impossible. A still further object is to provide a safety paper wherein 35 the chemically sensitive coloring matter will not be merely superficial. And a still further object is to provide a process for printing or making this safety paper which will incorporate a ground color in the paper in 40 a manner to not only render this color waterproof, but at the same time make it sensitive to such chemical reagents as are used for removing ground color.

The invention consists primarily in the 45 process of making safety paper for negotiable instruments and other commercial paper, embodying therein printing upon paper with a chemically sensitive water-soluble ink, subjecting said paper to a drying process 50 whereby said ink and its vehicle are caused to penetrate the fibers of the paper, and thereafter precipitating the coloring matter of the ink and separating it from its vehicle; and in such other novel steps 55 and processes, and in the product secured thereby, all as hereinafter set forth and de-

scribed, and more particularly pointed out in the claims hereto appended.

Referring to the drawings,

Figure 1 is a view of the face of a check 60 or other negotiable instrument after having been subjected to the first step in the process or after having been impregnated with the water soluble ink.

Fig. 2 is a vertical section showing the 65 article while being treated in the fixing bath;

Fig. 3 is a view illustrating the third step 70 in the process or the washing of the product to remove the vehicle therefrom;

Fig. 4 is a view illustrating the fourth or final drying step; and

Fig. 5 illustrates the final step or the treatment by a supersensitizing solution.

Like letters refer to like parts through- 75 out the several views.

In the practice of my invention, I apply to the surface of a sheet of paper a coating of a coloring matter carried by a water soluble vehicle, this vehicle preferably consisting of a composition consisting of gum arabic 32%, glycerin 48% and water 20%. To this vehicle I add coloring matter in such proportions as to secure the intensity 80 of the color desired, from five to ten per cent. of this coloring matter having been found in actual practice to produce a satisfactory result. If desired, an inert base such as barium sulfate may be added in quantities of about 5 to 20% or even higher 85 if desired. This base however is not essential to the water soluble ink used in carrying on my process, but it is often found in inks of the class used.

The colors I prefer to use are brilliant 90 green, orange Y, scarlet 2R methylene blue, etc.

After the paper has been printed with this water soluble ink, I allow it to stand for a sufficient period to dry, the printed surface 100 thereof, preferably applying heat thereto to cause the water soluble vehicle and the coloring matter carried thereby to penetrate the fibers of the paper and thus thoroughly impregnate the entire body of the paper 105 with the ink and with the coloring matter forming a part thereof. The slow drying or the application of heat is similar to the aging process in textile printing and has the effect of softening the paper and loosening 110 the fibers in a degree to facilitate the absorption of the water soluble ink.

The paper having thus been thoroughly impregnated with the water soluble ink, the next step is to render this ink insoluble through the precipitation of the coloring matter by means of a fixing medium which will convert the same into an insoluble lake. This step separates the coloring matter from the water soluble vehicle and causes it to enter the fibers of the paper. At the same time the coloring matter is rendered extremely sensitive to chemical reagents, so that the application of such reagents to the paper will affect not only the surface but the entire body of the paper and thus make it practically impossible to restore the paper to its former condition. The coloring matter through this step becomes firmly attached to or embedded in the fibers of the paper as distinguished from being merely a superficial coating. The fixing medium is dependent upon the nature of the colors employed and may vary so long as it has the characteristic of precipitating the coloring matter held by the water soluble vehicle in the manner described.

In connection with brilliant green or methylene blue, I use tannic acid as the medium, while with orange Y or scarlet 2R I use barium chlorid.

It will be apparent that simultaneously with the precipitating of the coloring matter, the water soluble vehicle will be carried away by the fixing medium, thus thoroughly separating the coloring matter and its vehicle on the finished product.

If desired, the paper may be rendered still more sensitive to the action of reagents by immersing after it has dried in a solution of potassium ferrocyanid or an equivalent reagent as indicated in Fig. 5.

It will be observed that by practising my process, the coloring matter is rendered insoluble and is firmly attached or embedded in the fibers of the paper, a result which is secured in part by the absorption of the water soluble ink by the paper during the second step of the process and a subsequent precipitation thereof through the fixing ink. This condition is not true where a water proof ink having an oily vehicle is employed, as while the oily vehicle will render the surface of the paper water-proof or impervious to moisture, it does not make the coloring matter sensitive to chemical reagents which is an essential characteristic of my invention.

By the foregoing process, I secure a product consisting of the printed paper, the fibers of which have attached thereto or embedded therein water insoluble coloring matter sensitive to chemical reagent, which col-

oring matter is devoid of the vehicle used to permit it to be applied to the paper.

Having described my invention, what I claim as new and desire to secure by Letters Patent is:—

1. The herein described process of printing negotiable instruments or other commercial paper embodying therein printing upon paper with a chemically sensitive ink, causing said ink to penetrate the fiber of the paper and thereafter subjecting the paper to a fixing medium whereby the coloring matter of the ink is attached to and embedded in the fiber of the paper and its sensitivity to the action of chemicals retained. 70

2. The herein described process of printing negotiable instruments or other commercial paper embodying therein printing upon paper with a chemically sensitive ink containing a soluble vehicle and color, causing said ink to penetrate the fibers of, or be absorbed by, the paper and thereafter simultaneously precipitating the coloring matter and rendering it insoluble and removing the vehicle through the action of a fixing medium which will not affect the chemical sensitivity of said coloring matter. 80

3. The herein described process of printing negotiable instruments or other commercial paper embodying therein printing upon paper with a chemically sensitive ink containing a soluble vehicle and color, causing said ink to penetrate the fibers of, or be absorbed by, the paper, thereafter simultaneously precipitating the coloring matter and rendering it insoluble, removing the vehicle through the action of a fixing medium which will not affect the chemical sensitivity of said coloring matter and thereafter 100 subjecting the paper to a chemical reagent for rendering said coloring matter still more sensitive to chemicals. 90

4. A safety paper for negotiable instruments or other commercial paper having chemically sensitive coloring matter embedded in the fibers of the paper, said coloring matter being devoid of a vehicle. 105

5. A safety paper for negotiable instruments or other commercial paper having chemically sensitive water insoluble coloring matter embedded in the fibers of the paper, said coloring matter being devoid of a vehicle. 110

In testimony whereof I have signed my name to this specification in the presence of two subscribing witnesses. 115

LLEWELLYN REECE.
